CLAIM

The ornamental design for a beveled buckle, as shown and described.

DESCRIPTION

FIG. 1 is a perspective of a beveled buckle showing my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The portions of the figures illustrated in broken lines are provided for illustrative purposes only and form no part of the claimed design.
